UNITED STATES PATENT OFFICE.

OSBORN P. LOOMIS, OF NEWPORT NEWS, VIRGINIA.

APPLIANCE FOR INDICATING EXPLOSIVE PRESSURES IN GAS-ENGINES.

1,143,639.

Specification of Letters Patent. Patented June 22, 1915.

Application filed March 13, 1909. Serial No. 483,096.

To all whom it may concern:

Be it known that I, OSBORN P. LOOMIS, a citizen of the United States, residing at Newport News, in the county of Warwick 5 and State of Virginia, have invented certain new and useful Improvements in Appliances for Indicating Explosive Pressures in Gas-Engines, of which the following is a specification.

10 The object of my invention is to provide a device by which the pressures at which gas-engines are operating can be conveniently ascertained. This information enables the engineer to tell at once whether proper 15 pressures are being developed in the explosive space of the engine cylinder, and in the case of multiple cylinders enables him to ascertain if all are alike in effort, if any are lacking, and to what extent. The usual way 20 of ascertaining these pressures is by means of the steam-engine indicator. While this instrument affords accurate results, its use is attended by much trouble and inconvenience, and it does not afford continuous indications 25 of pressure. I have accordingly devised an arrangement which will secure this result and the following is a description of the same, reference being had to the accompanying drawing, in which the figure is a 30 view in elevation, parts being, for convenience, shown in section.

In my prior Patent No. 1,087,883, patented Feb. 17, 1914, I have shown and described a damping device for pressure gages 35 which can and has been used for indicating pressures in explosive engine cylinders, but the following invention has certain features of improvement.

40 Referring to the drawings, Figure 1 is a view in elevation, parts being shown in section; Figs. 2, 3, 4 and 5 show modified forms of valve.

In Fig. 1 of the drawing, 1 is a pressure gage of any usual type which is connected to 45 a casing 5, this casing being divided by a diaphragm M into two chambers A and D. The lower chamber A which may be termed the sediment-collecting chamber receives the pressure gases from the engine through a pipe H having at its end an extension E screwed through the bottom of the chamber A and having its opening at the upper part thereof and in proximity to the bottom of the diaphragm M. The bottom of this 50 chamber A is provided with an opening nor-

mally closed by a stop-cock F. The soot, carbonized material, etc., carried from the engine cylinder by the gases, are thrown against the bottom of the partition M and drop down into the chamber A, whence they 60 can be blown out occasionally along with the water which is always present, by opening the cock F. The pressure gases pass from the chamber A upward through the pipe G, secured to the diaphragm M, and thence 65 into the pipe B which is coiled as shown to provide an extended frictional surface for the gases flowing therethrough. The combined throttling and cushioning effect produced by the pipe B and the expansion or 70 air chamber D prevents any violent fluctuations of the gage needle and makes it practically dead beat. The operation of this portion of the device is the same as that disclosed in my prior application above re- 75 ferred to.

The gases are admitted from the engine cylinder to the pipe H through a retardative return valve J which is mounted in a valve-casing, the lower part 2 of which is 80 provided with a bore I, opening into a chamber 9 which is in turn closed by a plug 3, into which is screwed a coupling 10 which connects the valve-casing with the pipe H. In case it is not convenient to make connection at the top of the valve the connection 85 can be made at the opening closed by the plug K, the opening in the top being then of course correspondingly plugged.

The valve J which is constructed to permit 90 free flow of pressure gases in one direction and to greatly retard the flow in the other, is, as shown, seated on the bottom of the chamber 9 in such a position as to normally close the bore I. An increase of pressure in 95 the engine cylinder causes the valve to rise and allows the pressure to be transmitted through the openings 4 into the tube H.

As the pressures of a gas engine are pulsating, and at times even non-existent, it is 100 desirable to secure the highest indications possible on the gage in order to detect small differences in cylinder pressures, by which leaks, imperfect firing and other defects are discovered. These results are accomplished 105 by the valve which has just been mentioned.

When the engine is started the valve J is lifted and allows the pressure to pass around its stem and enter the space above it, and thence to be exerted through the pipe 110

H through the damping chambers to the gage. After a few explosions the pressure on top of the valve J (which retards the gas from returning during small intervals) 5 will reach a maximum for a given load at which the engine is operating. Should the explosive pressures in the cylinder then increase, the valve J will allow it to enter the pipe H which will be indicated by a rise of 10 the gage pointer. Should the explosive pressures within the cylinder decrease, the pressure in the pipe H (and consequently on the gage) will also decrease, due to the fact that the tightness of the valve J is design- 15 edly made imperfect and slowly allows the pressure to leak back into the explosive space until a certain definite relation between the two pressures is reached.

By the combination of parts it is ap- 20 parent that there is afforded a continuous dead beat indication of a pressure bearing a certain relation to that actually occurring in the cylinder at the time indicated. Practical results show that these indicated pres- 25 sures are not initial, neither are they mean effective pressure, but are somewhere be- 30 tween the two.

While I have described the apparatus as particularly adapted for use in connection 35 with the indication of gas-engine pressures, it is of course equally adapted for use in any locality where the measurement of pulsating and widely varying pressures is de- 40 sired.

While I may, as above described, rely upon the leakage of the valve J to permit release of pressure within the gage mechanism, I may provide a small leak opening or vent through the body of the valve itself. 45 This vent may be, as shown in Fig. 2, a fine bore K², through the body of the valve J². As holes of such small diameter as are required for this purpose, are difficult to make, I can arrive at the same result by the means shown in Fig. 3, in which the bore K³ through the body of the valve J³ is made of considerable size, and the ends are partially closed as shown by setting over the edges of the openings at the ends of the bore with a suitable tool. Or I may make the bore K⁴ through the stem of the valve of a diameter convenient to drill, and then roll down a portion of the stem to contract the inside bore to the extent desired, the end 50 of the main bore being contracted as shown in Fig. 4, or left of its original diameter.

The mode of operation of the valve pro- 60 vided with the leak vent, is substantially the same as described with reference to the construction shown in Fig. 1. The leak vent is so small as not to permit, during the intervals between the pulsations of pressure, any diminution of pressure sufficient to affect the practical accuracy of the gage indica- 65 tions, while the leak so obtained does serve

to allow with sufficient rapidity, the escape of compressed gas in the system so that the gage may indicate a decreased or fallen pressure occurring in the cylinder.

Instead of providing the valve with a leak vent, or relying upon the usual leakage of the valve, I may adopt the form of vented retardative return valve shown in Fig. 5, in which P represents pins of hard material, such as steel, which are set into the face of the valve seat, which is of material not so hard as the pins. These pins, three being shown (although the particular number used is not material), are arranged as shown in a circle beneath the edge of the valve J. The wear of the surface of the valve seat is slightly greater than that of the harder pins, so that the pins soon form slight projections above the surface of the valve seat, thereby preventing the valve from fitting with entire snugness to its seat. Moreover, as the pins do not fit into the holes with absolute exactness, a slight pas- 80 sage way for the gases exists between the upper ends of the pins and the holes, thereby assisting to afford the slight leakage de- 85 sired. This form of leakage valve pre- 90 cludes the possibility of the leak-vents being closed by fine material in suspension in the steam or hot gases. The operation of 95 this form of valve is the same as that be- 100 fore described.

The direct connection of the leakage-valve casing to the source of explosive pressure, as in automobile engines, is particularly ad- 105 vantageous, as the actual pressure in the engine cylinder is thereby indicated without the diminution, due to friction in the connecting pipe, which occurs if the leak- 110 age-valve is located at or near the gage. It is to be noted further that as there is no leakage to the outer air there is no possibility of loss of residual pressure in the engine cylinder, should the engine be tempo- 115 rarily stopped, and the necessity of frequent "recranking" is thereby avoided.

In operating gas engines of considerable size, it has been found that small pockets or clearance spaces leading from the cylinder are liable to hold flame and cause what is known as "back firing" which is the ignition and exploding of the mixture in the cylinder before the proper time in the stroke and seriously retarding the operation of the engine. In making connections 120 for indicators to cylinders of gas engines such openings are necessary and I find that with my system of pressure indicators as described in this specification, attached to such openings the slight return-leakage of a 125 compressed gas, cooled by the exposure of the pipe H and air chamber casing 5, obviates the difficulty of "back firing" as it is evident that a small portion of the cooled 130 highly compressed gas leaking into the clear-

ance space through the passage I, expands many times and pushes into the exhaust the hot gases and flame that may be contained therein and at the same time cooling the 5 lining so that any further mixture will not ignite.

I claim:

1. In combination, a casing having therein two chambers connected together by a flow 10 retarding passage, one chamber being connected to a pressure gage and the other chamber being provided with means for removing collected sediment.
2. In combination, a reservoir having 15 therein two chambers connected together by a throttled passage, one chamber being connected to a pressure-gage, and the other chamber being provided with a pipe for delivering pressure-gases thereinto, and means 20 for removing sediment from such chamber.
3. The combination of a valve-casing adapted to be connected to an engine-cylinder, a retardative return valve in such casing, a pipe connected thereto and arranged 25 to deliver into the lower or sediment chamber of a gage mechanism, such mechanism comprising a gage, a casing to which the gage is connected, an apertured partition

dividing the casing into two chambers, a flow-retarding device opening into the upper chamber and means for permitting removal of sediment from the lower chamber.

4. In combination, a casing having therein two chambers connected together by a throttled passage, one chamber being connected to a gage and the other chamber being provided with deflecting surfaces arranged to throw away the sediment from the gases passing toward the gage.

5. In a fluid-pressure actuated pressure 40 gage, a closed cushion chamber having an indicating mechanism directly connected thereto, a chamber for pressure fluid, a conduit containing a throttled section connecting the two chambers, a pipe for connecting 45 the pressure fluid chamber to an engine-cylinder, and a valve in such pipe constructed to permit free flow of pressure gases in one direction and to greatly retard the flow in the other.

In testimony whereof, I affix my signature in presence of two witnesses.
